UNITED STATES PATENT OFFICE.

SIDNEY W. JONES, OF TUCKER, UTAH.

AUTOMATIC TYPE-WRITER FEED.

1,028,026.

Specification of Letters Patent.

Patented May 28, 1912.

Application filed September 18, 1911. Serial No. 649,852.

To all whom it may concern:

Be it known that I, SIDNEY W. JONES, a citizen of the United States, residing at Tucker, in the county of Utah, State of Utah, have invented certain new and useful Improvements in Automatic Type-Writer Feeds; and I do hereby declare the following to be a full, clear, and exact description of the invention, such as will enable others skilled in the art to which it appertains to make and use the same.

This invention relates to automatic paper feeds for typewriters.

An object of the present invention is to provide a rack which may be attached to an ordinary typewriter and will support telegraph blanks and the like, a pressure plate being provided for holding the sheets in frictional engagement with the feed rollers. A further object of the invention is to provide a novel spring controlled pin which pierces the sheets and holds the same together, the sheets being successively detached from the pin by the feed rollers. With the above objects in view the invention consists in certain novel details of construction and combination of parts herein-after fully described and claimed, it being understood that various modifications may be made in the minor details of construction within the scope of the appended claims.

In the accompanying drawings forming part of this specification:—Figure 1 is a side elevation of a typewriter equipped with a paper feed embodying my improvements. Fig. 2 is a plan view of the paper feed applied to a typewriter. Fig. 3 is a rear elevation of the paper feed applied to a typewriter with the lower portion of the typewriter broken away. Fig. 4 is a longitudinal sectional view taken on the line 4—4 Fig. 2. Fig. 5 is a front elevation of the paper feed applied with parts of the typewriter broken away. Fig. 6 is a fragmentary detail perspective view of the pressure plate and its mountings. Fig. 7 is a side elevation of a pneumatic feed roller with parts broken away. Fig. 8 is a detail perspective view of the needle bracket.

Referring now to the drawings in which like characters of reference designate similar parts, 10 designates the frame, 11 the platen, and 12 the spacing bar of an ordinary typewriter. Attached preferably to the spacing bar near each end thereof are brackets 13 and 14 which serve as supports for the

paper rack. These brackets may be of any preferred form and may be attached in any desired manner to the spacing bar or other suitable part of the carriage, and in the present instance, the bracket 13 is shown substantially U-shape in outline and having one leg bolted as shown at 15 to the spacing bar, and its opposite leg bolted as shown at 16 to the underneath face of the paper rack. The mating bracket 14 is substantially U-shape in outline and has its bight bolted as shown at 16' to the spacing bar while its terminals are bolted to the underneath face of the paper rack.

The paper rack comprises spaced longitudinal angle iron side bars 17, the upper ends of which are connected by an angle iron top bar 18, and the lower ends of which are connected by a plate 19 the lowermost edge 20 of which extends beyond the side bars and is curved in outline to conform to the curvature of the typewriter paper support. The side bars are spaced apart sufficiently to permit of the insertion therebetween of telegraph blanks or the like, and for supporting various sizes of blanks, a pair of substantially L-shaped standards 21 are secured to the side bars, and are connected by a rod 22, to which are attached the eyes 23 of angle iron hangers 24, the eyes being adjustably secured to the rod by means of set screws 25. The angle iron hangers are moved into engagement with the edges of a bundle of blanks and perform the dual function of supporting the blanks and forming guides to direct the sliding movement of the blanks downwardly to the platen. To accommodate blanks of different lengths, the top bar 18 is adjustably secured to the side bars of the paper rack, the preferred manner of attaining this end being to form the bar with upstanding ends 26 which bear along the inner faces of the side bars and are equipped with inverted U-shape straps 27 which straddle the side bars, set screws 28 being threaded through suitable openings formed in the outer legs of the straps, and being advanced into engagement with the outer faces of the side bars to clamp the top bar in any desired position longitudinally of the side bars. It will thus be seen that by virtue of the adjustably mounted angle iron hangers 24 and adjustably mounted top bar 18, that the paper rack may be adjusted to fit various sizes of sheets.

For detachably securing all of the sheets

together, a bar 29 is terminally secured to the before mentioned upstanding ends 26, and is preferably square in cross section. An angle iron clip 30 is provided on one leg with an eye 31 which loosely encircles the bar and is equipped with a set screw 32 for securing the clip in any desired position longitudinally of the bar. The mating leg of the clip is formed in its top face with a groove 33 which slidingly receives the lowermost leg of a U-shaped bracket 34, a set screw 35 being inserted through a slot in the bracket leg and a suitable registering opening in the clip leg to permit of adjustment of the bracket longitudinally of the clip leg. Alined square openings 36 are formed in the bracket legs and slidingly receive a pin 37, this pin being provided with a counterbore at its lower end for the reception of a needle 38, the latter being detachably secured in the counterbore by means of a set screw 39. A thumb nut 40 is formed on the upper end of the pin and permits of the pin being forced downwardly until the needle penetrates a number of the uppermost sheets of paper in the paper rack. A helical spring 41 is seated on the pin and bears with its opposite terminal convolutions against the lowermost leg of the bracket 34 and against a boss 42 formed on the pin, this spring exerting a constant downward pressure upon the pin to facilitate manual insertion of the needle in the uppermost sheets, and furthermore when the uppermost sheets have been fed to the typewriter platen as will presently be described, this spring automatically causes the needle to penetrate the next underlying sheets so that all of the sheets in the rack will be pierced without manual attention after the first few sheets have been manually pierced as above described. The needle thus operates to secure together the sheets adjacent to their uppermost edges, and the sheets are torn in succession from the needle by the hereinafter described feed rollers.

The feed rollers 43 are preferably three in number and are fixed to a shaft 44 which is journaled in standards 45 fixed at their lower ends to the side bars. Each feed roller consists of a grooved rubber or similar disk 46 which is clamped between the metallic circular washers 47, one of the washers being provided with an exteriorly threaded nipple 48 upon which the mating washer is threaded up into abutting contact with the disk. The nipple loosely fits the shaft, and is secured thereto through the instrumentality of a set screw 49. While a friction roller of this kind is suitable for most purposes, it is not intended to limit the construction to this form of roller since the roller may consist of a pneumatic tire 50 carried upon the rim of a wheel 51 such as

is shown in Fig. 7. This style of feed roller will not require as great a tension of the hereinafter described pressure plate for pressing the sheets of paper against the roller as the above described disk roller. It is to be understood that during rotation of the shaft 44 that the feed rollers bear upon the uppermost sheet of paper and advance the same downwardly into engagement with the paper guides of the platen. 75

For actuating the feed shaft, a spur gear 52 is loosely fitted to the shaft, and over this gear and the platen rotating knob 53 a link chain 54 is trained, idlers 55 being mounted on the standard 13 and bearing 80 against this chain to maintain the same taut. The gear 52 is connected to the feed shaft by a clutch mechanism about to be described, and when this clutch mechanism is in operative position, and the platen actuating 85 knob is rotated, the feed shaft will be rotated and the sheet of paper fed to the platen.

The clutch mechanism consists of a cylindrical sleeve 56 which is slidably fitted 90 on the feed shaft, connection between the shaft and sleeve being made by a pin 57 passed through the sleeve and bearing loosely within a slot 58 formed in the shaft. A tube 59 is arranged axially in the sleeve, 95 and houses a pin 60, a helical spring 61 surrounding the shank of the pin and bearing with its opposite terminal convolutions against a cap 62 which closes the open end of the tube and against the head of the pin. 100 The head of the pin is designed to be selectively engaged in one of a pair of notches 63 formed in the shaft, manual sliding of the pin toward or away from the gear 52 operating to engage the pin in either of the 105 desired notches. Formed on the confronting faces of the sleeve and gear are opposing lugs 64, and when the sleeve is moved to its limit of movement in the direction of the gear, these lugs contact. During such 110 contact of the lugs, it being understood that the sleeve is locked to the shaft by the spring controlled pin being engaged in one of the notches of the shaft, the gear will be locked to the shaft and cause the rotation thereof. To disengage the clutch, the sleeve is slid outwardly on the shaft until the spring controlled pin engages in the mating notch of the pair of notches in which position of the parts the lugs are disengaged. 115 120

To effect the proper working of the device, the lower ends of the sheets of paper held within the paper rack must be held with considerable pressure against the feed rollers, and to attain this end I provide a 125 pivoted pressure plate 65 which is loosely fitted between the side bars of the frame and is curved upwardly at its lower end as shown at 66 to underlie and conform to the curvature of the feed rollers. The pressure plate 130

65 is equipped on its top face with a yielding covering element 67 such as leather, rubber or the like. The lowermost sheet of paper bears without slipping upon this element. Fixed to the lowermost face of the plate adjacent its upper edge is a longitudinal bar 68 the opposite ends of which are equipped with upstanding fingers 69 to which are riveted or otherwise secured as 10 shown at 70 levers 71, these levers extending along and being pivoted to the side bars as shown at 72. The pivots of the levers thus form pivots upon which the pressure plate may be rocked, and it will thus be seen that 15 the pressure plate is pivoted to the side bars and the free end portion underlies the pressure rollers. Helical springs 72' are fixed to the free ends of the levers and are secured to the outwardly bent upper ends of the 20 standards 45 through the instrumentality of adjusting bolts 73. These springs normally exert an upward pull upon the free ends of the levers so that the upper end of the pressure plate is depressed while the 25 free lower end is elevated and forces the sheets of paper into tight frictional engagement with the feed rollers.

To hold elevated the pivoted end of the pressure plate in order that the free end of 30 the pressure plate may be depressed and the paper supply replenished from time to time, notched bell crank levers 74 are pivoted at their elbows to the standards 45 as shown at 75, the free legs of the bell crank levers 35 being flattened to provide thumb rests 76. The fingers 69 may be moved until the notches in the fingers engage over lugs 76' on the fingers, thereby rocking the pivoted end of the pressure plate upwardly, and the 40 free end out of contact with the feed roller in which position of the parts the paper supply may be replenished. Upon release of the thumb rest after the paper supply has been replenished, the helical springs 72' will 45 turn the pressure plate to its operative position.

For guiding the end of the sheet into engagement with the platen as it emerges from the feed rollers, a curvilinear guide plate 50 77 is provided at its upper edge with eyes 78 which loosely encircles the feed shaft.

The guide plate overhangs the bottom plate of the rack, and cooperates with the latter in directing the paper emerging from the feed rollers downwardly to the rear of and 55 into engagement with the platen.

What is claimed, is:—

1. An automatic paper feed including a paper support, a feed roller at the lower end thereof, an adjustable pressure plate carried 60 by said support and bearing against said feed roller, and a spring controlled pin carried by said support adapted to pierce material carried thereby and hold the same together. 65

2. An automatic paper feed including a paper support, a feed roller thereon, a pressure plate pivotally secured to said support and frictionally engaging said feed roller, and a spring controlled pin adjustably 70 mounted on said support and adapted to pierce the material thereon.

3. An automatic paper feed including a paper support, a feed roller thereon, adjustable stops for engaging the sides and ends 75 of various sized blanks of paper carried by said support, a pressure plate pivoted on said support and frictionally engaging said feed roller, means for manually releasing the pressure plate so that the paper supply 80 may be replenished, and a spring controlled pin adjustably mounted on said support adapted to pierce the paper thereon.

4. An automatic paper feed including a paper support, a roller thereon, means for 85 rotating said roller, a spring controlled pivoted pressure plate on said support frictionally engaging said roller, manually releasable means for moving said pressure plate out of engagement with said roller, a bar extending transversely across said support, a bracket adjustably mounted on said bar, and a spring controlled pin carried by 90 said bracket adapted to pierce the sheets of paper on said support. 95

In testimony whereof, I affix my signature, in presence of two witnesses.

SIDNEY W. JONES.
